TOY ANIMAL FIGURE

Mary L. Lawser, Radnor, Pa.

Application July 22, 1958, Serial No. 51,897

Term of patent 7 years

(Cl. D34—2)

Fig. 1 is a frontal view in perspective of my new design for a toy animal figure;

Fig. 2 is a perspective as viewed from the rear;

Fig. 3 is a side elevational view;

Fig. 4 is a front elevational view;

Fig. 5 is a rear elevational view; and

Fig. 6 is an inverted plan view.

I claim:

The ornamental design for a toy animal figure, as shown.
